UNITED STATES PATENT OFFICE.

JOHN M. FEDDERS, OF BUFFALO, NEW YORK, ASSIGNOR TO FEDDERS MANUFACTURING COMPANY, INC., OF BUFFALO, NEW YORK, A CORPORATION OF NEW YORK.

RADIATOR.

1,139,961.

Specification of Letters Patent. Patented May 18, 1915.

Application filed July 31, 1914. Serial No. 854,266.

To all whom it may concern:

Be it known that I, JOHN M. FEDDERS, a citizen of the United States, residing at Buffalo, in the county of Erie and State of New York, have invented new and useful Improvements in Radiators, of which the following is a specification.

This invention relates to the core for radiators such as commonly employed for cooling the water of automobile explosion engines and has for its object to produce such radiators at low cost, of a greater durability and high cooling efficiency.

In the accompanying drawings: Figure 1 is a fragmentary elevation of an automobile radiator having its core constructed in accordance with my invention. Fig. 2 is a vertical transverse section of the same taken in line 2—2, Fig. 4. Fig. 3 is a horizontal section taken in line 3—3, Fig. 2. Figs. 4 and 5 are vertical longitudinal sections taken in the correspondingly numbered lines in Fig. 2. Fig. 6 is a fragmentary perspective view of one of the metal strips employed in the construction of my improved radiator core.

Similar characters of reference indicate corresponding parts throughout the several views.

30 In the organization of the radiator shown in the drawings the same comprises an upper water inlet header, a lower water outlet header 2, a plurality of upright water passages, channels or tubes 3 communicating at their upper and lower ends, respectively, with the upper and lower water headers, and a plurality of horizontal air passages, channels or tubes 4, preferably of hexagonal form in cross section, extending lengthwise 40 from the front to the rear side of the radiator, a vertical row of such air passages being formed between every two adjacent water passages.

The core of the radiator which contains the water and air passages comprises a plurality of sheet metal strips each of which is bent or shaped to form a plurality of webs 5, 6 which are arranged zig-zag relatively to each other, each web forming a wall of one 50 of the air passages. The strip is so constructed as to form a plurality of pairs of plait webs 5 and a plurality of pairs of seat webs 6, the same being so disposed that the members of each pair of seat webs are arranged adjacent to each other and the mem-

bers of each pair of plait webs are also arranged adjacent to each other, and the several pairs of seat webs alternate with the several pairs of plait webs.

The longitudinal edges or corner between the members of each pair of seat webs are bent from the inner toward the outer side of this corner so as to form a longitudinal concave seat 7 at the apex between two companion seat webs which constitute a pair. 60 Each of the strips is also provided with a plurality of plaits 8 each of which forms a wall for each of two adjacent air passages. Each of the plaits has its two sides or flaps connected at the crown or outer edges thereof while the base or inner edges thereof are connected, respectively, with the opposing edges of two adjacent plait webs of a pair so that this plait projects laterally from the outer corner between the respective plait 75 webs. The corner between the longitudinal edge of each plait web and the adjacent seat web is flattened as shown at 9. At its opposite edges each strip is provided with offsets 10 which project laterally therefrom on 80 that side opposite to the side of the strip from which the plaits are arranged. Strips of this form are assembled so that the crown of each plait engages with one of the concave seats 7 of one adjacent strip and forms a 85 plurality of hexagonal air passages therewith and so that the off-set of one strip engages with the off-set of another strip and forms a zig-zag water passage therebetween. The off-sets of the strips are connected with 90 each other so as to form a water tight joint between the same this being preferably effected by soldering them together. In like manner the upper and lower ends of the strips are connected with the upper and lower 95 headers to form a water tight joint between the water passages and the headers.

The strips are so assembled that the base of each plait on one strip is arranged opposite the corner between one plait web and the adjacent seat web of another strip with which it forms a water passage while the crown of this plait engages with the seat between two seat webs of another strip with which it forms a plurality of air passages. 105 Owing to the flattening of the corners between each plait web and the adjacent seat web these parts of each strip are spaced apart from the convex side of those portions of the strip which are deflected inwardly 110

into the water passages to form the seats for the crowns of the plaits, thereby providing clearance at these places and producing unobstructed water passages of zig-zag 5 shape from the upper inlet to the lower outlet header.

Although it is not necessary to flatten those corners between the seat webs and plait webs of one strip which are arranged 10 opposite the bases of the plaits of another strip, it is preferable to do so inasmuch as the tools for making these strips can be made uniformly and no particular care on the part of the workmen is necessary in assembling the strips when making a core inasmuch as, by this means it is immaterial whether the plaits of one strip are arranged in line with one or another flattened corner of another strip to secure a free flow through 15 the respective water passage. When the several strips are thus assembled the air passages or tubes of one row are staggered relatively to the air passages or tubes of adjacent rows so that alternate rows of air 20 passages terminate at the upper and lower headers in whole air passages or tubes and half air passages or tubes. In order to exclude the water in the headers from the upper and lowermost air passages of each row 25 30 the ends of every two strips between which a row of air passages is formed are connected by a seam 11, as shown in Fig. 2, or by any other suitable manner.

The construction of my radiator core is 35 comparatively low in cost, the same is very strong and capable of withstanding the heavy strains to which it is subjected in use, and it presents a large cooling surface so that the same is very efficient in operation.

40 I claim as my invention:

1. A radiator core having water and air passages arranged at right angles to each other and comprising a plurality of strips each of which is bent to form a plurality of 45 webs arranged zig-zag relatively to each

other so that each web constitutes one wall of a hexagonal air passage and the several webs form a plurality of pairs of seat webs and a plurality of plait webs, said pairs of seat webs alternating with the pairs of plait webs, a plurality of concave seats each arranged at the adjacent longitudinal edges of a pair of seat webs, and a plurality of plaits forming walls of adjacent air tubes and each plait having the crown of its sides 50 connected and the base thereof connected respectively with the opposing longitudinal edges of a pair of plait webs, said strips being assembled so that the crown of each plait engages with one of the concave seats 55 of one adjacent strip and forms a plurality of hexagonal air passages therewith and is spaced apart from another adjacent strip to form a zig-zag water passage therebetween, each of the corners between the meeting edges of a plait web and an adjacent seat web of one strip which is opposite the seat of another strip being flattened so as to space said corner apart from the convex side of said seat. 70

2. A radiator core having water and air passages arranged at right angles to each other and comprising a plurality of strips which are of zig-zag form and assembled so that each strip forms a plurality of air 75 passages with one adjacent strip and a water passage with another adjacent strip, and one strip of each pair having some of its corners deflected to form concave seats which are engaged by parts of an adjacent strip 80 and the companion strip of said pair having some of its corners deflected to form clearance spaces between the same and an adjacent seat of the other strip. 85

Witness my hand this 29th day of July, 1914.

JOHN M. FEEDERS.
